UNITED STATES PATENT OFFICE.

FLAEL SIMONSON, OF STERLING, ILLINOIS.

ACETYLENE-GAS GENERATOR.

SPECIFICATION forming part of Letters Patent No. 696,765, dated April 1, 1902.

Application filed December 20, 1899. Renewed October 3, 1901. Serial No. 77,451. (No model.)

To all whom it may concern:

Be it known that I, FLAEL SIMONSON, a citizen of the United States, residing at Sterling, Illinois, have invented certain new and useful Improvements in Acetylene-Gas Generators, of which the following is a specification.

The object of my invention is to make a machine or apparatus for the generation of what is known as "acetylene gas" which will be adapted for use in dwelling-houses, factories, and other isolated places and in which the calcium carbide used in the generation of such gas may be used, whether in lump or powdered condition, without requiring special knowledge or skill on the part of the person in charge of the generator, so that no evil or undesired results need be apprehended from mistakes or carelessness; and my invention or improvements consist in the features and details of construction hereinafter described and claimed.

In the drawings, Figure 1 is a perspective view, in sectional elevation, of my improved gas-generating apparatus shown broken away to disclose the interior construction and to show the generator-bell partially withdrawn from its normal rotative position; Fig. 2, a sectional view of the gasometer and gas-generating apparatus; Fig. 3, a vertical section taken on the irregular line 3 of Fig. 2; Fig. 4, a detail view of the bearing for the main shaft used to impart rotation to the generator-bell; Fig. 5, an enlarged detail central section taken through one side of the gas-generating apparatus; Fig. 6, a sectional view taken on line 4 of Fig. 5; Fig. 7, a perspective view of a carbid-holder and its supporting and directing well with the triggered latch for supporting the carbid-holder until it is to be released; Fig. 8, an enlarged fragment in perspective showing a portion of the generator-bell casing and the air-venting flue; Fig. 9, a side view of the gasometer, showing the mechanism for translating the vertical movement of the gasometer-bell into a rotary movement for turning or revolving the generator-bell; Fig. 10, a perspective detail view of the means or mechanism by which such translation is effected; Fig. 11, a top view of the bell-locking arm and main driving-shaft, which rotates the generator-bell; Fig. 12, a detail central section of the generator-bell,

hub, and driving shaft and connections and a side view of the bell-locking arm; Fig. 13, a plan view of a fragment of casing of the 55 gas-generating chamber and carbid-holders and supporting and directing wells in which I illustrate a modified form of means for releasably supporting the carbid-holders; Fig. 14, a vertical section through a supporting 60 and directing well and carbid-holder, illustrating the modified means for maintaining the carbid-holder in place until it is desired to release it; Fig. 15, an exterior side elevation of the modified form of supporting and 65 directing well, showing a slot in its side in which the trigger-arm is intended to work; and Figs. 16 and 17 illustrate still another modified form for supporting the carbid-holders in their wells until it is desired to release them. 70

In making my improved gas-generating device I employ a gasometer, comprising a body portion or main receptacle A, intended to contain water, and a bell portion B, telescopically mounted within the body portion and adapted to slide or move partially up and down as the quantity of the gas contained in the same varies from time to time. In these respects the gasometer may be of the usual 80 construction.

The gasometer is supplied with gas from my improved gas-generator by a pipe C, located between the gasometer and generator, which pipe at one end enters the outer casing of the generator and has connection with the gas-eduction pipe C', which leads from the gas-space of the generating-chamber above the body of water therein. The other end of the pipe C enters a chamber C² in the 90 bottom of the gasometer, from which chamber a gas-eduction pipe C³ leads to the gas-receiving space beneath the gasometer-bell above the body of water in the gasometer. The generated gas flows from the gas-space 95 of the generator through the eduction-pipe C' and connecting-pipe C into the chamber C², and from thence through the pipe C³ to the receiving-space beneath the gasometer-bell to pass out from the gasometer-bell through 100 the eduction-pipe B³ to the point of consumption or combustion.

My generating apparatus comprises an outer casing D, which may be made of any

desired size as to height and diameter. It is of course made of suitable metal, but preferably of galvanized sheet-iron. I also arrange an inner casing D' within the gas-generating apparatus, and between the outer and inner casings I arrange a generator-bell D², adapted to be turned in partial revolutions intermittently by mechanism hereinafter described and for a purpose which will presently appear. The inner casing is intended to afford means for supporting the carbid-holders and their wells, as hereinafter explained. The space above the inner casing and inclosed by the generator-bell forms a gas-chamber D³, in which the carbid-holders are stored above the surface of the water before the carbid is converted into gas and from which the gas as it is generated is conveyed to the gasometer. This gas or storage chamber is annular in form, and its inner wall is formed by a cylindrical partition D⁴, which depends from the top of the bell into the gas-generator within the inner casing. This partition is shown as cylindrical in the drawings; but I do not desire to confine myself to any special form for it, as its form is not material to the operation of the machine.

The holders G, intended to contain the calcium carbid, are preferably cylindrical in form, as illustrated in the drawings, although I do not intend to confine myself to any particular form in cross-section. The holders should, however, have a longer vertical than transverse dimension and should be open only at the top or upper end. The transverse dimensions of the holder should bear a proper relation to the quantity of carbid which they are intended to contain, so that when submerged, as hereinafter explained, only a desired restricted area of carbid surface will be exposed to the action of the water, and so that as the carbid is slaked and the gas generated all the residuum resulting from the slaking of the carbid will be carried out at the top of the holder with the escape of the gas, so that such residuum will be prevented from settling upon the unslaked carbid and interfering with the action of the water thereon. By employing elongated holders I am able to use a maximum quantity of carbid while presenting only a comparatively small area of its surface at the upper end to the action of the water, so as to secure the advantages above suggested. I provide the elongated carbid-holders with a weight α at their lower ends or bottoms sufficient to hold them submerged in the water while gas is being generated. This weight will of course vary with the size of holders that are used, and so I will simply say that it should be sufficient to counteract the tendency of the gas as it is generated to cause the holder to rise to the surface. I arrange the carbid-holders in wells G² of a size and shape adapted to receive them. These wells are supported in any suitable way, but preferably by attaching them to the top of the in-

ner casing, so as to form a circumferential row or ring, as shown in the drawings. The wells are intended to be of a desired depth 70 and so that the carbid-holders when sunk in them will be sufficiently submerged in the water. They are open both at the top and bottom; but means are employed of any desired kinds to prevent the carbid-holders 75 from falling entirely through them and out at their bottoms when released. As shown, a lip g' is turned on the bottom of the well, against which the holder will rest. Their upper ends are intended to be covered by hinged 80 covers G³. It is preferred that the carbid-holders when placed in the wells shall have their upper ends extended slightly above the tops of the wells and that the hinged covers shall rest flatly upon the tops of the holders, 85 so as to prevent moisture, caused by condensation or otherwise, from getting admission to the holders in injurious quantities. This will be understood from an inspection of Figs. 5 and 7 of the drawings, where the 90 holders are shown in place in the wells with the lid down in one case and up in the other. In order to permit the guiding-wells to be all inserted and removed together as an entirety, I fasten or mount them upon the inner surface 95 of a hoop G', which is of a size to permit it to be inserted within the casing D', on which it may rest and be held by a flange g'', as shown in Figs. 1 and 3. As shown, each holder has a cross-rod g at the top, by means 100 of which and a suitable hooked rod or other means the holder can be raised from the bottom of its well.

Means must of course be employed to hold or maintain the carbid-holders in their up 105 positions until it is desired to release them and have them submerged in the water for the generation of gas. To effect this, I provide the wells with lateral slots g² cut in them, as particularly shown in Fig. 15. These 110 lateral slots g² should be at a point far enough down in the wells to enable the carbid-holders to be held with their upper ends at the desired elevation. The means which I employ in connection with the lateral slot for 115 supporting the carbid-holders in their up or stored position are well illustrated in Figs. 5 and 7. They comprise a bearing J, illustrated in the drawings in the form of a sleeve d, arranged vertically on the outside of the 120 well, and a rod arranged in the bearing with a proper handle or trigger portion f, projecting out from the well, and with a finger portion e, extending into the lateral slot g² in the well when the handle or trigger extends outward. The carbid-holder rests on the inwardly-projecting finger until the handle or trigger f is turned to one side, which causes the rod to rotate in its bearing until the finger is moved out of the slot and from under 125 the holder, upon which the holder will drop into the well. In short, the means shown in Figs. 5 and 7 for maintaining the carbid-holder in its up position may be briefly de-

scribed as a rod arranged in a bearing on the side of the well and so bent that one end projects out, while the other projects into the lateral slot in the side of the well so as to receive and sustain the weight of the carbid-holder, so that as the rod is rotated by pressure applied to the projecting trigger the finger will be moved out from under the carbid-holder. To effect this turning, so as to permit the carbid-holder to drop into the well and to be submerged when desired, I arrange on the side of the partition D⁴ depending from the generator-bell a laterally-projecting member or lug K, which is carried around as the generator-bell is rotated or turned from time to time. The projecting triggers f when the carbid-holders are in their up position extend into the path of this lateral lug, so that as it is moved around with the generator-bell it strikes against them successively and turns them the requisite distance to move the fingers e out from under the carbid-holders and permit them to drop. The projecting lug contacts against each of the triggers successively and only as the generator-bell is moved around in its partial rotations. As each carbid-holder is released it drops into the body of water H while still remaining in and being guided and directed by the well in which it is placed, thus maintaining it in a perpendicular position. This permits the water which fills the lower part of the well and which flows in through the lateral slot g³ in its side to flow into the open top of the carbid-holder, so as to act upon the top exposed surface of the carbid and cause gas to be generated. The gas as generated passes up and through the open top of the holder and carries with it such particles of the decomposed carbid as are not converted into gas, but left as residuum. As the top surface of the carbid is thus consumed and removed another surface is exposed, so that the operation continues without interruption until all of the carbid in the holder has been acted upon by the water and consumed.

The generator is provided with an inclined bottom D⁵, sloping downward toward the center from the walls of the generator-casing. This permits the residuum thrown out of the carbid-holders to settle and accumulate in a mass, so that it can readily be removed in any desired way.

It is desirable in the operation of my generator to secure the results that I desire that the triggers shall be operated upon automatically and only as the generation of gas is needed, so that a constant supply of gas can be maintained in the gasometer for purposes of use and a steady flow to the point of consumption maintained. This requires that means shall be employed to cause the generator-bell to be returned or rotated by stages and at intervals determined by the quantity of gas in the gasometer, so that after the operation of the machine has been once commenced it will be continued automatically until all of the carbid-holders have been suc-

cessively submerged and their contents consumed in the generation of gas. In order to effect this intermittent rotation of the generator-bell, I utilize or make use of the vertical movements of the gasometer-bell by employing means to translate or convert the vertical movements of such gasometer-bell into rotative movements of the generator-bell. In order to do this, I connect to the gasometer-bell a rod L, which reciprocates therewith, which is well illustrated in Figs. 9 and 10. This rod has near its lower end a pin h, adapted in its downward movement to engage one arm j of a bent lever L², carrying a pawl at its free or outer end. The rod L is formed with an angle-bar, having the sides l' and l'' at right angles to each other. The slot k is formed in the sides l'', and the pin h is arranged on the side l', so that the pin crosses the arm j to secure the contact with it, as already described. The bent lever L², through means of its pawl, is adapted to drive or rotate a ratchet-wheel I³, mounted on a counter-shaft L⁴, on which the bent lever is also pivoted, so that as it is rotated it imparts a rotative movement to such counter-shaft. This counter-shaft is provided with a miter-gear which meshes or engages with the teeth of a miter-gear on the main shaft E, arranged in the generator, the pair being indicated by the letter L⁵, as will appear from Figs. 3 and 4. As, therefore, the ratchet-wheel is intermittently rotated it imparts an intermittent rotation to the main vertical shaft E, which carries the generator-bell D². As the gasometer-bell is moved up under an accumulating quantity of gas it carries the rod L up with it, and the arm j of the pawl device, being extended through the slot k in the rod, is lifted or carried up, and at the same time the other end of the bent lever, with its pawl, by which the teeth of the ratchet-wheel are intermittently engaged, is carried down or back, slipping over the teeth. To prevent the ratchet-wheel from rotating backward during the above operation, I employ a stop-latch l, which engages with one of the teeth of the ratchet-wheel, so as to prevent retrograde motion, while permitting it to be rotated forward, as desired. This stop-latch and its arrangement and operation will be well understood by an inspection of Fig. 9 of the drawings. In this way the bent lever and pawl and ratchet-wheel are adjusted in position, so that as the bell of the gasometer descends, owing to the consumption of the gas, the pin h when the gasometer-bell has descended to a predetermined point contacts with the arm j of the pawl device, so as to carry it down and at the same time carry the other end of the pawl device, with its dog now in operative engagement with the teeth of the ratchet-wheel, upward or forward, so as to turn or rotate the ratchet-wheel and the counter-shaft on which it is mounted and through the miter-gears, the main generator-bell shaft, so as to impart rotation to the genera-

tor-bell. As such bell is rotated the lug K on the depending partition D⁴ strikes against one of the protruding triggers f, so as to turn it and release a carbid-holder, as already explained, which, being released, sinks into the well and is submerged in the water. The generation of gas that ensues causes the bell of the gasometer to be again carried up and the arm L and the pawl-and-ratchet device to be again moved into position to be operated by the descending bell, when the gas is sufficiently consumed to cause it in sinking to sufficiently lower the rod to again move the pawl device and the ratchet-wheel forward and release another carbid-holder, as already described, and the operation already explained is repeated. As shown, an intermediate housing or casing S is located between the gas-generator and the gasometer, which housing or casing surrounds the ratchet device for rotating the top of the gas-generator and is provided with a tube forming a guide for the rod L; but such casing is not a necessity and can be dispensed with.

25 The generator-bell D² is open at its lower end and disposed over and about the gas-generating chamber, as already explained. In order to mount the bell so that it can be rotated, as already explained, it is provided with

30 a central hub or boss m in the form of a tube, which extends down from the top or apex of the bell and which is open at both ends, with the upper opening, however, angular in cross-section, having a flat face on one side, as will be understood from an examination of Fig. 11. The depending tube of the hub or boss when the bell is in its down position surrounds the upper end of the main shaft E and rests upon a stationary or non-rotative sleeve

35 p, surrounding the main shaft and secured to the bottom of the outer casing, so as to permit the shaft to pass through said sleeve. This will be understood from an inspection of Figs. 1 and 12, where the parts just described are illustrated, except that in Fig. 12 the depending portion of the hub m is omitted and the bell allowed to rest directly upon the sleeve p. The upper end of the main shaft is cut away and made with an angular

40 or flat face to fit the angular or flattened hole in the upper end of the hub or boss, so that the two must rotate together, and thus connect the bell in rotative engagement with the main shaft. As the bell is unrestrained

45 throughout its lower portion and the upper end of the gas-chamber under the bell is closed, there is a tendency in the generation of the gas to lift the bell upward which must be provided against and which I prevent by means

50 of the locking-arm M, depending from an eccentric pivot which secures said arm to the main shaft, as will be understood from an examination of Fig. 12. The lower end of the arm thus hangs normally and by gravity in

55 such a position that its lower end protrudes so as to hang above the top of the hub or boss m, and thus prevent the bell from being

moved upward by the pressure of the gas. To release the bell when for any purpose it is desired to do so, the swinging or pivoted arm is simply pressed in toward the main shaft until it permits the hub to pass it, when the bell may be bodily withdrawn and access to the carbid-holders and gas-chamber permitted. In this way the pressure of the gas beneath the bell provides a floating bearing, as it were, so that the bell can readily and easily be rotated without the friction that otherwise would exist. The depending partition D⁴, extending down from the inside of the bell, which I have already described, forms a central chamber N, surrounding and inclosing the upper portion of the main shaft. As this partition extends down into the water no gas can pass from the generating-chamber D³ 85 into this central chamber surrounding the shaft. This obviates the necessity of using stuffing-boxes in the connection between the shaft and the bell, as will readily be understood from an examination of Fig. 1. To prevent a compression of air in this central chamber, vents s may be employed to permit the escape of the air as the bell is being lowered into place.

In order to permit the adjustment of the 95 gas-generator bell in position, it is necessary to provide some means to permit the air to escape from the gas-generating chamber as the bell is lowered and to prevent the access of air to such chamber when the bell is in its 100 down position. In order to effect this automatically, I arrange a U-shaped pipe-channel O, (shown more particularly in Figs. 6 and 8,) which channel communicates with the interior of the generating-chamber through the port u and into the outer chamber through the open end or port v. When the bell is being adjusted in place, the channel serves as a vent for the air which is caught or inclosed in the gas-generating chamber, so as to permit it 105 to escape, while when the bell is in its down position the ports u and v are submerged under the water, so that a water seal is secured and all escape of gas from and all entrance of air into the gas-chamber prevented. When the 110 bell is lifted up and removed, the water entering the port v will flow through the pipe and permit the air to follow it and enter the gas-generating chamber, so that a vacuum is prevented. This results from the fact that 115 the atmospheric pressure exerted on the water in the pipe causes it to be siphoned out through the opening u into the gas-generating chamber, which is free from a corresponding atmospheric pressure.

In Figs. 13, 14, and 15 of the drawings I have shown a modified form of the means employed for holding or supporting the carbid-holders in their wells, which consists of arms f', hinged loosely to the inner casing and projecting across the interior of the well through the lateral slots g² formed in them, as already described. The lateral slots must of course be of sufficient length to permit the arms to

be sufficiently entered under the carbid-holders to support them, and the free ends of the arms f' must project far enough beyond the wells to permit the lug K to strike against them and move them back out of the lateral slots to permit the holder to sink in the wells. The projection of the free end of the arm f' is to be one that will produce a short engagement therewith of the lug for a distance only 5 sufficient to move the arm and drop the holder, and then the arm can drop into the space between the wells after being moved completely out of the slot in the wall of the well.

In Figs. 16 and 17 I have shown a still further slight change in the form of the holding device, where I have located the bearing d' for the trigger and finger entirely below the carbid-holders instead of above, as in Figs. 5 and 7, for instance, and in which the trigger 10 f^2 is extended at its inner end to form a stop or finger e' to lie beneath and engage the bottom of the carbid-holder and sustain the holder in its elevated position, and in order to permit the passage of the finger e' to engage the holder the wall of the well has a slot g^3 for the admission of the end of the finger. It also has the bent end g^5 of the finger, which strikes against the holder and which limits or 15 stops its movement inward when turned into its supporting position.

Of course it will be understood that proper means in the nature of safety or emergency valves, such as are well known, may be used to allow the gas in the gasometer to escape 20 after it has reached a desired or predetermined volume or pressure, so as to prevent the bell from being raised by the gas beyond a desired height. As various forms of automatic release or safety valves or devices may 25 be employed for this purpose, many of which are well known and in use, I do not deem it necessary to show or describe one in connection with my present apparatus, but leave the constructor at liberty to employ such as 30 he may prefer.

While I have described the construction and operation of my improved acetylene-gas-generating machine or apparatus with considerable minuteness of detail, yet I desire it 35 to be understood that I do not propose to limit or restrict myself to mere details of construction further than the same may be specified or called for in the claims, as I contemplate changes in form, construction, and design 40 without, however, departing from the spirit of my invention.

What I regard as new, and desire to secure by Letters Patent, is—

1. In an acetylene-gas generator, a long and 45 narrow carbid-holder presenting a small area in cross-section of exposed surface for the carbid and formed of an imperforate body an open top and a closed and weighted bottom, means for maintaining the carbid-holder in a perpendicular position with its top above the surface of the water, and means for releasing

the carbid-holder and permitting it to be submerged in the water and aided in its descent and held when submerged in a vertical position by the weighted bottom, substantially as 70 described.

2. In an acetylene-gas generator, a desired number of long and narrow carbid-holders each presenting a small area in cross-section of exposed surface for the carbid and each 75 formed of an imperforate body an open top and a closed and weighted bottom and normally held with the open tops above a body of water contained in the generating-chamber, and means for automatically releasing 80 each carbid-holder to permit it to descend and be submerged in the water, whereby the water enters at the top only and acts only on a small area of exposed carbid, substantially as described.

3. In an acetylene-gas generator, a desired number of long and narrow carbid-holders, each holder presenting a small area in cross-section of exposed surface for the carbid and each formed of an imperforate body an open 90 top and a closed and weighted bottom and normally held with the open top above the surface of a body of water in the generating-chamber, a correspondingly-shaped guiding-well for each carbid-holder in which the holder 95 is received and held vertically and guided, and means for releasing each holder from its raised position in its well to permit it to descend and be assisted in its descent and submerged in the body of water in the generating-chamber and held in a vertical position 100 when submerged by the weighted bottom for the admission of water at the open top only, substantially as described.

4. In an acetylene-gas generator, a desired 105 number of long and narrow carbid-holders, each holder presenting a small area in cross-section of exposed surface for the carbid and each formed of an imperforate body an open top and a closed and weighted bottom and 110 normally held with the open top above the surface of a body of water in the generating-chamber, a correspondingly-shaped guiding-well for each carbid-holder in which the holder is received and held vertically and 115 guided, means for supporting the carbid-holders in the wells in a raised position, and means for releasing the carbid-holders successively and at intervals from the raised position to permit them to descend and be assisted in their descent and submerged in the 120 body of water in the generating-chamber and held in a vertical position when submerged by the weighted bottom for the admission of water at the top of each holder only, substantially as described.

5. In an acetylene-gas generator, a rotatable bell, a main shaft extending up through the generator beneath the bell and on which the bell is mounted and by which it may be 130 rotated, means for limiting the upward movement of the bell on the shaft, and means be-

neath the bell for automatically imparting rotation to the main shaft at desired intervals, substantially as described.

6. In an acetylene-gas generator, a casing containing a body of water, a rotatable bell arranged in the casing, means for intermittently imparting partial rotation to the bell, a desired number of carbid-holders located in juxtaposition side by side circumferentially around the interior of the casing at its upper end, each carbid-holder open at one end and with the open end normally supported under the bell above the body of water, means for supporting the carbid-holders individually, and means actuated by the partial rotation of the bell for automatically and successively releasing the carbid-holders and permitting them to be submerged in the water, substantially as described.

20 7. In an acetylene-gas generator, a casing containing a body of water, a rotatable bell arranged in the casing, means for intermittently imparting partial rotation to the bell, a desired number of carbid-holders located in juxtaposition side by side circumferentially around the interior of the casing at its upper end, each carbid-holder open at one end and with the open end normally supported under the bell above the body of water, a guiding-well for each carbid-holder in which it is received and guided, each well containing a single carbid-holder, means for supporting the carbid-holders individually in the wells, and means actuated by the partial rotation of the bell for automatically and successively releasing the carbid-holders and permitting them to be submerged in the water, substantially as described.

30 8. In an acetylene-gas generator, a casing containing a body of water, a bell arranged in the casing, a desired number of guiding-wells within the casing under the bell and extending into the body of water contained in the casing, carbid-holders open at the top and slidably arranged in the wells with the active surface of the carbid in the holders above the surface of the water, supports for maintaining the carbid-holders so arranged, a trigger device adapted to actuate the supports and release the carbid-holders, means for automatically operating the trigger device to permit the carbid-holders to be submerged in the water, and means for maintaining the carbid-holders when released and submerged in a stationary upright position while the action of generation takes place, substantially as described.

40 9. In an acetylene-gas generator, a casing containing a body of water, a bell arranged in the casing, a desired number of circumferentially-disposed and perpendicularly-arranged guiding-wells within the casing under the bell and extending into the body of water contained in the casing, carbid-holders open at the top and arranged in the wells with the active surface of the carbid in the holders above the surface of the water, re-

movable supports for maintaining the carbid-holders so arranged, a trigger device adapted to actuate the supports and release the carbid-holders, a rotatable member adapted to successively engage the trigger devices and remove the supports and permit the carbid-holders to be submerged in the water, and means for automatically imparting rotation to the rotatable member at desired intervals, substantially as described.

70 10. In an acetylene-gas generator, a water-chamber, a rotatable generator-bell arranged therein, a gas-generator chamber, a desired number of guiding-wells circumferentially disposed and perpendicularly arranged within the gas-chamber under the bell and extending into the body of the water, carbid-holders open at the top and slidably arranged in the wells with the active surface of the carbid in the holders above the surface of the water, removable supports for maintaining the carbid-holders so arranged, a trigger device adapted to actuate the supports and release the carbid-holders, an engaging member carried by the rotatable bell adapted to successively engage the trigger devices and remove the supports and permit the carbid-holders to be submerged in the water, and means for automatically imparting rotation to the bell at desired intervals, substantially as described.

80 11. In an acetylene-gas generator, a desired number of guiding-wells circumferentially disposed and perpendicularly arranged within the gas-chamber and extending into the body of water, carbid-holders open at the top and slidably arranged in the wells with the active surface of the carbid in the holders above the surface of the water, movable supports for the carbid-holders, a rotatable bell arranged in the generator, means carried by the bell for actuating the movable supports of the carbid-holders, a main shaft on which the bell is mounted and by which it may be rotated, and means for automatically imparting rotation to the main shaft at desired intervals, substantially as described.

90 12. In an acetylene-gas machine, a gas-generator having a generating-chamber containing a body of water, a desired number of long and narrow carbid-holders arranged in the chamber, each holder presenting a small area in cross-section of exposed surface for the carbid and each formed of an imperforate body an open top and a closed and weighted bottom and normally held with the open top above the surface of a body of water in the generating-chamber, means for supporting each carbid-holder vertically in its normal position, a gasometer, means for conveying gas from the generating-chamber to the gasometer, and means automatically operated at a predetermined point of consumption of gas in the gasometer for releasing the carbid-holders from their raised position to permit them to descend and be assisted in their descent and submerged in the body of water in

the generating-chamber and held vertically when submerged by the weighted bottom for water to enter the holder at the top only, substantially as described.

- 5 13. In an acetylene-gas machine, a gas-generator, a rotatable bell arranged in the generator, a desired number of carbid-holders open at one end and with the open end normally supported under the bell above a body 15 of water contained in the generator, means for supporting the carbid-holders, a gasometer, means for conveying gas from the generator to the gasometer, means for intermittently imparting partial rotations to the bell 20 set into operation when the gas in the gasometer reaches a predetermined point of consumption, and means for automatically releasing the carbid-holders and permitting them to be submerged in the water actuated 25 by the partial rotation of the bell, substantially as described.

14. In an acetylene-gas generator, a carbid-holder having an imperforate body an open top and a closed and weighted bottom, with 25 the body of greatly-increased length as compared with its width, forming an open-top closed chamber for receiving the carbid and held in a vertical position by the weighted bottom permitting the live carbid to be exposed 30 to the action of water from the top only with a small area of surface exposure, a generator-bell, and a well for the holder located beneath the generator-bell and having an open top and bottom and having the holder 35 releasably supported in the upper portion of the well to descend therein when released and be maintained in perpendicular position in its descent with the open top uppermost, substantially as described.

- 40 15. In an acetylene-gas generator, a generating-chamber partially filled with water, a vertical well within the generating-chamber having an open top and bottom for the admission of water to its interior from the bottom, 45 and a carbid-holder having an imperforate body an open top and a closed bottom with the body of an increased length as compared with its width, forming an open-top closed chamber 50 for receiving carbid and means for supporting the carbid-holder in the well with its bottom projecting into the water of the well, the water to form a seal between the body of the holder and the wall of the well and prevent the downward flow of generated gas, substantially as described.

16. In an acetylene-gas generator, a generating-chamber partially filled with water, a vertical well within the generating-chamber having an open top and bottom for the admission of water to its interior from the bottom, a carbid-holder having an imperforate body an open top and closed bottom with its body of increased length as compared with its width, forming an open-top closed chamber for receiving carbid and inserted in the upper portion of the well, means for supporting the holder in the well with its bottom projecting

into the water of the well forming a water seal against the downward flow of generated gas, and means for releasing the holder to descend 70 and be submerged in the water of the well to permit the water to enter the holder at the top, whereby the gas first generated will pass to the bottom of the holder and fill the interstices between the particles of carbid in the holder 75 and exert an upward pressure in the holder, substantially as described.

17. In an acetylene-gas generator, a generating-chamber partially filled with water, a desired number of vertical wells within the 80 generating-chamber, each provided with a hinged flap or cover for the top and each having an open top and bottom for the admission of water to its interior from the bottom, a carbid-holder for each well, each carbid-holder 85 having an imperforate body an open top and a closed bottom with its body of an increased length as compared with its width, forming an open-top closed chamber for receiving carbid and inserted in the upper portion of its well, means for supporting each carbid-holder in the upper portion of its well with its bottom projecting into the water of the well, and means for releasing each holder from its raised position and permitting it to descend to the 95 lower portion of the well and be submerged in the water therein, whereby the upward pressure of the gas through the confined space will remove the residuum and the hinged covers will prevent the discharge from entering the adjoining wells and protect the carbid of the holders therein from the injurious effect of the discharge, substantially as described.

18. In an acetylene-gas machine, the combination of a generator comprising an outer casing for water and provided with a bottom inclining toward the center, a pipe rising from the apex of the bottom and terminating beneath the gasometer-bell, a rotatable gasometer-bell removably mounted on an upright shaft and comprising an outer casing and a central depending inner casing secured to the top and extending downward into the water and forming a chamber around the upper end 115 of the pipe, and a depending guide from the gasometer-bell surrounding the top of the central pipe for guiding the movements of the bell, substantially as described.

19. In an acetylene-gas machine, the combination of an angle-iron rod arranged outside of the gasometer-casing and suspended in a vertical position from the gasometer-bell and having a slot through one of its flanges and a pin on the other crossing in front of the slot, a ratchet-wheel, a pawl engaging the ratchet-wheel, a bent lever carrying the pawl and having one arm double and the double arm straddling the ratchet-wheel and provided with a hole through the double arm for mounting the lever on the shaft of the ratchet-wheel for a pivot to be engaged in action by the pin in the downward movement of the rod 125 and swung downward on its pivot and to be 130

engaged by the lower end of the slot in the rod in the upward movement of the rod and carried to its normal position when at rest, substantially as described.

- 5 20. In an acetylene-gas machine, a ratchet-wheel mounted on a shaft and secured thereto, a bent lever having one arm double and the double arm straddling the ratchet-wheel and carrying a pawl to engage with the teeth 10 of the ratchet-wheel and advance the wheel when the lever is swung or turned downward, the double arm of the bent lever being provided with a hole between the end and the angle for mounting the lever on the shaft 15 of the ratchet-wheel as a pivot, the ratchet-wheel shaft extending horizontally to a point beneath the generator and provided with a beveled gear at its inner end, a vertical shaft extending upward through the generator 20 within a central pipe therein and adapted to engage at its upper end the bell of the generator so as to rotate the same, a beveled

gear near the lower end of the vertical shaft to engage with the bevel-gear of the horizontal shaft for imparting rotation to the vertical shaft from the horizontal shaft, and a pawl pivoted to a fixed point for preventing the ratchet-wheel from turning back while the bent lever is being drawn to its initial position, substantially as described. 25

21. In a gas-generator, the combination of a rotatable generator-bell having in its top a central hole for the passage of a main or driving shaft end, and a main or driving shaft for rotating the bell and on the upper 30 end of which the bell is removably mounted to permit its withdrawal for recharging the generator, leaving the shaft in position in the generator, substantially as described. 35
